UNITED STATES PATENT OFFICE.

MONROE GREEN, OF BROOKLYN, NEW YORK.

RULER.

SPECIFICATION forming part of Letters Patent No. 294,870, dated March 11, 1884.

Application filed June 12, 1883. (No model.)

To all whom it may concern:

Be it known that I, MONROE GREEN, of Brooklyn, in the county of Kings and State of New York, have invented a new and Improved 5 Ruler, of which the following is a full, clear, and exact description.

The object of my invention is to provide a new and improved ruler, by means of which lines can be drawn readily and rapidly and 10 without soiling or blotting the paper.

The invention consists in a ruler on which a longitudinal frame is held, between the wires of which a stylographic or like pen is held, which, if drawn lengthwise through the frame, 15 draws a line. The said frame is pressed upward by springs, so that the point of the pen will not be on the paper when the pen is not in actual use.

Reference is to be had to the accompanying 20 drawings, forming part of this specification, in which similar letters of reference indicate corresponding parts in both the figures.

Figure 1 is a plan view of my improved ruler. Fig. 2 is an end elevation of the same. 25 A frame, A, formed of two parallel rods or wires, B, united at the ends, and placed a short distance apart, is placed on a ruler, C, in such a manner that one wire B will be above the edge of the ruler, and the other wire B will 30 be a short distance from the edge of the ruler, both wires being parallel with the ruler. The end pieces of the frame A rest on springs D, fastened to the ruler. The springs can consist of spring-strips secured on the top of the 35 ruler, or of spiral springs secured to and resting on projections E on the front edges of the ruler, which springs always press the frame upward, so that it will be raised above the top of the ruler. A short stylographic or like pen, 40 F, having a point of the usual construction, is held between the rods or wires B of the frame, the said rods or wires passing into notches or recesses in the pen. The rods thus hold the pen, but permit moving the same parallel 45 with the ruler. A suitable strip or wire, G,

is arranged along the edge of the ruler outside of and to guide the pen. The pen is provided with an ink-receptacle, H, which also serves as a handle. As the frame A is pressed upward, it keeps the point of the pen from the 50 surface of the sheet on which the ruler rests. If a line is to be drawn the pen is pressed down, whereby the point of the pen will come in contact with the paper, the springs E being compressed. The pen is then moved the 55 desired length along the ruler, and as soon as the pen is released the springs raise it again. As the pen is raised as soon as it is released, it cannot deface or blot the paper. As the pen is guided by the frame A, it will always draw 60 straight lines parallel with the ruler.

The pen used can be of any desired suitable construction.

Having thus described my invention, what I claim as new, and desire to secure by Letters 55 Patent, is—

1. The combination, with a ruler provided with a longitudinal frame forming ways, of a pen held in said ways and free to slide back and forth therein, substantially as herein 50 shown and described.

2. The combination, with a ruler, of a longitudinal frame held on the top of the same, springs for pressing the frame upward, and a pen held to slide in the frame, substantially 75 as herein shown and described.

3. The combination, with the ruler C, of the frame A, the springs D, for pressing the frame A upward, and of the guide-strip G, substantially as herein shown and described.

4. The combination, with the ruler C, of the frame A, held on the same, and the pen F, held between the wires or rods B of the frame, the pen being provided with recesses or notches for receiving the rods, substantially as herein 85 shown and described.

MONROE GREEN.
